NESTABLE MOBILE CART DISPLAY

Melvin O. Maisak, Florissant, and William H. Fullington, Ballwin, Mo., assignors to Pet Incorporated, St. Louis, Mo., a corporation of Delaware

Filed June 11, 1969, Ser. No. 17,655

Term of patent 14 years

Int. Cl. D12—02; D6—01

U.S. Cl. D80—9

FIG.1

FIG.2

FIG.3

FIG.4

FIG.5

FIG. 1 is a front perspective view taken from one end of a nestable mobile cart display embodying our new design,

FIG. 2 is a front elevational view thereof,

FIG. 3 is a cross-sectional view taken on line 3—3 of FIG. 2,

FIG. 4 is an elevational view mobile cart design taken from the end opposite to that shown in FIG. 1; and

FIG. 5 is a fragmentary rear elevational view thereof.

We claim:

The ornamental design for a nestable mobile cart display, substantially as shown.
